W. L. CLAY AND A. H. HALLOWELL,
INCENDIARY PROJECTILE,
APPLICATION FILED JAN. 30, 1919.

1,434,681.

Patented Nov. 7, 1922.

Inventor

W. L. Clay.
A. H. Hallowell

UNITED STATES PATENT OFFICE.

WALLACE L. CLAY, OF THE UNITED STATES ARMY, AND ANDREW H. HALLOWELL, OF FRANKFORD, PENNSYLVANIA.

INCENDIARY PROJECTILE.

Application filed January 30, 1919. Serial No. 274,076.

(FILED UNDER THE ACT OF MARCH 3, 1883, 22 STAT. L., 625.)

To all whom it may concern:

Be it known that we, WALLACE L. CLAY, Lieutenant colonel, Ordnance Department, U. S. A., at present stationed at Frankford Arsenal, and ANDREW H. HALLOWELL, resident of Frankford, Montgomery County, Pennsylvania, both citizens of the United States, have jointly invented an Improvement in Incendiary Projectiles, of which the following is a specification.

The invention described herein may be used by the Government, or any of its officers or employees in prosecution of work for the Government, or by any other person in the United States, without payment of any royalty thereon.

This invention relates to devices employed for effecting the commingling of inflammable gases or vapors to produce a rapid conflagration, more particularly of the buoyant gases of balloons and like dirigible structures, and has for one of its objects to produce a projectile having means for simultaneously producing an unobstructed opening in the balloon envelope and exposing portions of the charge of the projectile so that the vapors emanating therefrom will commingle with the gas of the balloon and produce a violent conflagration and destroy the balloon.

With these and other objects in view the invention consists in certain new and useful improvements hereinafter described and specifically set forth in the claims, and in the drawings illustrative of the preferred embodiment of the invention.

Fig. 1 is a longitudinal sectional elevation of the improved projectile complete.

Fig. 2 is a longitudinal sectional elevation of the shell or jacket.

Fig. 3 is an enlarged diagrammatic detail illustrating the construction and arrangement of the severing attachment.

Fig. 4 is a detached side view of the closing plug.

Fig. 5 is an end view of the dividing plug.

The improved device is designed to produce a conflagration by effecting the union or amalgamation of a plurality of gases by the action of a projectile when penetrating the envelope or closure of one of the gases or compounds, and the invention consists primarily in providing the projectile with means for cutting out a portion of the envel-

ope or "bag" of the balloon in its passage therethrough, thus insuring the free entrance of air and the more certain commingling of the gases.

The projectile may be of any required size to fit any size or form of fire-arm bore and comprises a shell or jacket formed with a cylindrical rear portion 10 and forward or pointed portion 11. The jacket is formed initially as shown in Fig. 2, with the rear end open and with a gas escape aperture 12 through the cylindrical portion, the aperture being initially closed by a plug of a substance fusible at low temperature, and adapted to be fused by the heat generated by the passage of the projectile through the gun barrel.

Formed upon the pointed portion of the jacket 11 near its juncture with the cylindrical portion 10, is an annular rib or flange 13 having a cutting edge.

The cutting edge of the rib 13 terminates within the lines of the cylindrical portion of the jacket as indicated by the dotted lines, so that the cutting edge will not be injured by contact with the rifling grooves of the gun barrel.

The body of the jacket immediately in advance of the rib is reduced as indicated at 15, to increase the width of the forward face of the rib and thus increase its efficiency.

The rear end of the jacket is closed by a plug 16 secured in position by "spinning" the material of the jacket over the rear end of the plug, as shown at 17 in Fig. 1. The plug is further secured by a cap or closing disk 18 of solder or the like.

At its forward end the plug 16 is reduced as shown at 19, and bearing against the reduced end of the plug is a filler member 20 having a plurality of longitudinally directed channels or passages 21 providing communication between the annular space produced by the reduced portion 19 of the plug and the interior of the jacket in advance of the spacer member.

The "charge" for the projectile, indicated at 22, is deposited within the jacket in advance of the spacer member 20, and may be of any suitable substance or compound, for instance phosphorus, and the opening 12 or aperture 12 communicates with the space surrounding the reduced portion 19 of the plug 16, while the channels 21 and the an-

nular space permit the emanations from the phosphorus to escape through the opening 12 when the closure thereof is "fused."

The improved device is designed more 5 particularly for use in first penetrating a structure, for instance a balloon gas bag, and then igniting the gas or other inflating medium of the balloon to destroy it.

The projectile being fired from a rifled 10 barrel is consequently rapidly rotated during its flight, and when it strikes its objective the rib or flange 13 tears an aperture in the envelope of considerably greater diameter than the body of the projectile, 15 thus permitting a correspondingly larger quantity of air to enter.

When the projectile is fired, the heat generated by its passage through the gun barrel fuses the plug 12 and permits the entrance 20 of air to cause the vaporization of the phosphorus. When the projectile strikes its objective, for instance the gas bag of a balloon, the point portion penetrates the bag, and when the flange 13 strikes the material of the balloon envelope 25 it cuts out a circular section fully as large and frequently larger than the diameter of the flange, thus insuring the entrance of a sufficient quantity of air to effect the

proper commingling of the gases to produce 30 the conflagration.

The presence of the flange does not interfere with the action of the projectile, or add materially to the weight or the expense 35 of manufacture.

Having thus described the invention what is desired to secure by Letters Patent is:

1. An incendiary projectile comprising a jacket having a cylindrical rear portion and a pointed forward portion, said cylindrical 40 portion having a gas escape aperture, and a severing flange upon the pointed portion of the jacket with its cutting edge within the lines of the cylindrical portion of the same and the material of the pointed portion reduced 45 in advance of the flange to increase its width.

2. An incendiary projectile comprising a jacket having a cylindrical rear portion and a pointed forward portion, and a severing 50 flange upon the pointed portion of the jacket with its cutting edge within the lines of the cylindrical portion of the same and the material of the pointed portion reduced in advance of the flange to increase its width.

WALLACE L. CLAY.
ANDREW H. HALLOWELL.
